DESIGN FOR A REBOUND DEVICE FOR A PIN-BALL GAME APPARATUS

Charles E. Caestecker, Chicago, Ill.

Application March 25, 1940, Serial No. 91,234

Term of patent 14 years

To all whom it may concern:

Be it known that I, Charles E. Caestecker, a citizen of the United States and a resident of Chicago, in the county of Cook and State of Illinois, have invented a new, original, and ornamental Design for a Rebound Device for a Pin-Ball Game Apparatus, of which the following is a specification, reference being had to the accompanying drawing, forming part thereof.

Figure 1 is an elevational view of a rebound device for a pin-ball game apparatus showing my new design; and

Figure 2 is a top plan view thereof.

I claim:

The ornamental design for a rebound device for a pin-ball game apparatus, substantially as shown.

CHARLES E. CAESTECKER.
